(57) CLAIM

The ornamental design for a handle for a screwdriver, as shown and as described.

DESCRIPTION

FIG. 1 is a perspective view of a handle for a screwdriver showing my invention;

FIG. 2 is a front view thereof, the rear view being a mirror image of it;

FIG. 3 is a left side view thereof, the right side view being a mirror image of it;

FIG. 4 is a top view thereof;

FIG. 5 is a bottom view thereof; and,

FIG. 6 is a perspective view of a handle for a screwdriver wherein the broken line showing of the shaft is for illustrative purposes only and forms no part of the claimed design.
